UNITED STATES PATENT OFFICE.

FRANK E. HOUSH, OF WINTHROP, MASSACHUSETTS.

LOOSE-LEAF BOOK.

1,162,485.

Specification of Letters Patent. Patented Nov. 30, 1915.

Application filed May 12, 1915. Serial No. 27,583

To all whom it may concern:

Be it known that I, FRANK E. HOUSH, citizen of the United States, residing at Winthrop, in the county of Suffolk and 5 State of Massachusetts, have invented new and useful Improvements in Loose-Leaf Books, of which the following is a specification.

My invention relates to loose leaf books 10 and is for an improvement in the construction of books such as are shown and described in United States Letters Patent granted to me May 7, 1912, No. 1,025,468.

A book made as shown and described in 15 the patent referred to holds the leaves or sheets in proper order so long as the covers are securely fastened to the binding strips and the full thickness of the stack of leaves is maintained therein, but it has been found 20 that when thin paper is used the sheets curl or are easily bent at the binding edges particularly at the slotted portions thereof and therefore are likely to slip out of engagement with the binding strip.

25 The particular object of the present invention is to provide a loose leaf book so constructed that it will securely hold thin leaves or sheets, prevent the curling or bending of the binding edges, permit the 30 removal of some of the sheets without liability of others being freed accidentally, and having a cover which can be opened out flat thus exposing for use practically all of the surface of the top sheet.

35 In the accompanying drawings: Figure 1 is a partial plan view of my improved book showing the same in open position; Fig. 2 is a side view of the book with the covers in closed position; Fig. 3 is an enlarged section on the line 3—3 of Fig. 1; Fig. 4 is a perspective view of the back cover plate of the book shown in Fig. 1 and two of the binding strips used therewith; Fig. 5 is a perspective view of one of the binding strips 40 hereinafter described; Fig. 6 is a longitudinal sectional view of one form of binding strip; Fig. 7 is a longitudinal sectional view of another form of binding strip.

Having reference to the drawings, A represents the rear side cover of my improved book and B the front side cover thereof, the back of the book, B', being hinged at b to the rear side cover A and at b' to the front cover B. The cover A comprises preferably a sheet metal plate, b², inclosed by a cloth or paper covering, b¹, integral with

the covering of sections B and B'. The plate, b², is provided near one end thereof with a pair of hooks, b³, formed by cutting and bending portions of the plate, b², and 60 these hooks are adapted to engage binding strips, C. The strips C are formed with an oblique tongue adapted to fit into the correspondingly oblique slots cut in the end of the stack of leaves, D. Each binding 65 strip, C, is preferably made from a single piece of sheet metal cut and bent so as to comprise a body portion, c', and two sides or wings, c², the tongue, c, being an inwardly bent portion integral with the body 70 portion, c'. After the binding strips, C, have been fitted into and upon the stack of leaves, D, each strip is then engaged with its respective retaining hook, b³, by sliding one of the sides or wings, c², thereof into 75 position under the hook, b³.

In the present invention the side pieces or wings, c², of the binding strip extend beyond the tongue, c, so that the binding strip engages and holds together the leaves of 80 the stack at both sides of the slot occupied by the tongue, c. This makes it practical to use much thinner leaves or sheets than heretofore, thereby increasing the capacity of 85 the book and at the same time allowing the withdrawal of one or more of the sheets, by pulling endwise thereon, without disturbing the others in the stack. This characteristic provides a construction that is particularly 90 adapted to sales books since while the leaves are normally held securely in place the top leaf or sheet after it has been written upon can be separately pulled out of the book without danger of accidentally removing the ones below it, thus avoiding the necessity of 95 providing perforated sheets as is now common. Another advantage is that the sheets when so detached from the order book may be filed for future reference in another binder of like construction, as by the removal in the manner described there is no 100 mutilation of the sheet itself.

To hold the binding strip, C, against sliding sidewise relatively to the hooks, b³, and working out of engagement with the slots 105 of the leaves, D, I form the plate, b², with abutment lugs, b⁴, bent up at right angles to said plate, one at each side of the stack, D. These lugs serve to prevent sidewise movement of the stack of leaves and binding strips when the same are engaged by the lugs b⁴.

The tongue, c , of the binding strips, C, is formed by slitting the body portion, c' , transversely near one end thereof and longitudinally near each side wing, c^2 , part way 5 toward the opposite end of the strip and bending obliquely inward the tongue or flap thus produced. This mode of construction provides a cross bar, c^3 , connecting the ends of the binding strip which gives rigidity to 10 the strip, assists in positioning the strip on the stack of leaves and prevents the curling or bending of the leaves at the corners thereof and at the edges of the slots. In Fig. 7 I have shown a binding strip made from 15 a single piece of metal bent to form two sides or wings slitted at one end and near each side thereof for a portion of its length, thus providing the tongue, c^4 , which is bent obliquely inward. Obviously this form of 20 binding strip requires less metal than the binding strip, C, above described.

I claim:

1. A loose-leaf book comprising a stack of leaves; a cover; hooks projecting from 25 said cover; binding strips adapted to engage with said hooks, each binding strip comprising a body having a back adapted to fit against the edge of the stack of leaves, and formed with an oblique tongue adapted to 30 fit into a slot in the stack of leaves, and having wings perpendicular to the back of the strip extending lengthwise of the body beyond the tongue so as to hold the leaves of the stack against displacement 35 at both sides of the slot.

2. A loose-leaf book comprising a stack of leaves; a cover; hooks projecting from said

cover; binding strips adapted to engage said hooks, each binding strip comprising a body having a back adapted to fit against the edge 40 of the stack of leaves and formed with an oblique tongue adapted to fit into a slot in the stack of leaves and having wings perpendicular to the back of the strip at each side of said tongue extending lengthwise of the body beyond the tongue in both directions so as to hold the leaves of the stack against displacement at both sides of the slot.

3. A loose-leaf book comprising a stack of 50 leaves; a cover provided with hooks; binding strips adapted to engage with said hooks and provided with oblique tongues adapted to be engaged with correspondingly oblique slots provided in the stack of leaves, the 55 sides of each strip being extended lengthwise of the latter beyond the tongue so as to overlie the stack at both sides of the slot engaged by said tongue; and a pair of abutments at each side of the stack to prevent 60 lengthwise sliding movement of the binding strips relatively to said hooks.

4. As a new article of manufacture, a binding strip consisting of a top and two depending sides; and a tongue connected 65 with the top near its center so formed as to lie obliquely between the sides of the strip.

Signed by me at Boston, Mass., this 28th day of April 1915.

FRANK E. HOUSH.
